ELECTRIC RADIANT HEATING

Joseph McOrlly, Wilkinsburg, Pa., assignor to
 Edwin L. Wiegand Company, Pittsburgh, Pa., a
 corporation of Pennsylvania

Application February 17, 1951, Serial No. 211,557

3 Claims. (Cl. 219—34)

1

My invention relates to electric radiant heating, and the principal object of my invention is to provide an improved heater of that type.

In the drawings accompanying this specification and forming a part of this application I have shown for purposes of illustration what I now consider to be the best mode of carrying my invention into practice, and in these drawings:

Figure 1 is a side view of the selected embodiment, with an end part of the housing structure in section;

Figure 2 is a face view of the heater of Figure 1, with one of the cover plates removed;

Figure 3 is a section on the line 3—3 of Figure 1;

Figure 4 is a section on the line 4—4 of Figure 1; and

Figure 5 is an enlarged face view of one of the heating element mounting means.

The illustrated heater comprises an elongated housing structure 11 preferably formed from extruded aluminum, provided along its rear surface with two longitudinally extending ribs 12 constructed to be gripped by suitable supporting clamps, and provided in its forward surface with an approximately parabolic concavity 13 having along each edge a recess 14 and a lip 15.

Closing the ends of the concavity 13 are end plates 16 secured to the housing structure 11 by machine screws 17, and mounted in the concavity 13 are a pair of divider plates 19 dividing the concavity 13 into an extended central section 20 and two relatively short end sections 21.

As herein shown, each of the end plates 16 comprises an angular extension 18, each of the divider plates 19 comprises an angular extension 22 serving as a cover for the respective end section 21, and each of the divider plates 19 is held in position by interengagement with the housing lips 15 and by machine screws 23 securing the outer end of the cover section 21 to the angular extension 18 of the respective end plate 16.

Mounted in the cavity 13, extending longitudinally thereof, is an elongated metal-sheath resistor-electric radiant heating element 24 traversing the central section 20, extending through apertures 25 in the divider plates 19, and including terminal pins 26 electrically insulated from the element sheath 27, and to the pins 26 are welded connection terminals 28 each comprising a screw-threaded aperture 29 and a screw 30 received in the respective aperture 29 and arranged to bind a supply conductor in electrical connection with the respective terminal 28 and thus with the respective terminal pin 26,

2

According to the present disclosure the radiant heating element 24 is designed to maintain the sheath 27 substantially at the temperature to radiate predominantly the particular wave length that may be desired, for example, infra red, and is approximately triangular in cross section and located substantially at the focus of the parabolic contour of the concavity 13, with one of its faces disposed substantially in a plane parallel to the plane of the two forward edges of the housing structure 11, whereby heat from that face is transmitted directly, and only the heat from the other two faces is required to be reflected.

Preferably the concave forward face of the housing structure 11 is overlaid by a thin sheet 31 desirably formed of anodized rolled aluminum, thus providing a reflecting surface affording higher reflection and less susceptible to deterioration, and inasmuch as it can be inserted at the conclusion of the manufacturing processes, avoiding the possibility of the surface being damaged during the manufacture of the heater.

For the purpose of supporting the element 24 the heater comprises two electrical insulating mounting bodies 32 disposed in the end portions 21 of the concavity 13, each secured in position by a machine screw 33 passing through a longitudinal aperture 34 in the respective body 32 and engaged in a cooperating screw threaded aperture in the respective end plate 16, and each comprising a longitudinal slideway 35 receiving the respective connection terminal 28, whereby the bodies 32 support the element 24 by means of the terminals 28.

In the present embodiment the terminals 28 are longitudinally movable in the respective slideways 35, thereby to provide for longitudinal expansion and contraction of the heating element 24 upon heating and cooling, and also to permit ready insertion or removal of the element 24, the element being removed by shifting it longitudinally in one direction to withdraw one of the terminals 28 from the respective slideway 35, swinging that end of the element 24 outwardly, and then shifting the element longitudinally in the other direction, to similarly withdraw the other terminal 28 from its slideway 35, and being inserted by the reverse of this procedure.

To prevent accidental displacement of the element, each of the bodies 32 is provided with a longitudinal recess 36 receiving the tail of the respective binding screw 30, but terminating short of the forward end of the body 32, thus providing an end wall 37 engaged by the tail of the

screw 30 when the screw is in normal seated position, and thereby preventing removal of the element unless and until the screw 30 has been moved to raised position.

In many instances it is advantageous to connect both supply conductors at the same end of the heater, and to this purpose the housing 11 is provided with a longitudinal channel 39 extending between the two end sections 21 of the cavity 13, overlaid by the reflector 31, and arranged to receive a conductor 39 extending from the binding screw 30 at the other end of the element 24 and connected by means of a binding screw 40 to a terminal plate 41 received in a second slideway 42 in the illustrated body 32 and provided with a further binding screw 43 for receiving the second supply conductor.

To permit connection of the supply conductors at either end of the heater, the other body 32 is of the same construction, so that the arrangement may readily be reversed, and to prevent accidental displacement of the terminal plate 41, each of the bodies 32 is provided with a longitudinal recess 44 receiving the tails of the screws 40 and 43, but terminating short of the forward end of the body 32, thus providing an end wall 45 engaged by the tails of the screws 40 and 43, and thereby preventing removal of the plate 41 unless and until the screws 40 and 43 have been moved to raised position.

As will be understood, the bodies 32, being of electrical insulating material, provide secondary insulation for the element 24, and to complete this insulation the element is received in the divider plate apertures 25 in electrical insulating bushings 46 each comprising two complementary sections 47 together forming a complete separation between the element 24 and the respective divider plate 19.

As appears particularly in Figure 1, in the present embodiment each bushing section 47 is provided with a peripheral groove 48 receiving the wall of the respective divider plate 19, whereby the bushings 46 are normally retained in position, but are readily removable through the open side of the aperture 25 upon removal of the respective divider plate 19 from assembled position.

If the length of the element 24 between the plates 19 is such that the element is likely to deform from rectilinear, desirably the heater comprises one or more intermediate plates, not shown, each of which may be supported from the housing structure lips 15 similarly to the plates 19, and each of which is desirably provided with a further bushing 46 thereby to maintain the secondary insulation of the element 24.

To provide for entrance of the supply conductors, in the present embodiment each end portion of the housing structure 11 is provided with an opening 50 preferably screw threaded to accommodate an insulating bushing, conductor conduit, cable fitting, or the like, depending on the form of wiring.

To provide for assembling a plurality of heaters in side by side relation, in the present embodiment each side of the housing structure 11 is provided with a longitudinally extending undercut groove 51 arranged to receive one end of each of one or more tie members, such as the member 52, the other end or ends of which are similarly received in the similar groove along the adjacent side of the adjacent heater, and preferably the ends of the members 52 are angularly movable in the respective grooves 51, thereby to

permit the heaters to be disposed in adjustable angular relation.

As will be understood, various changes and modifications may be made, and therefore the present disclosure is to be regarded as illustrative only, and the scope of my invention is as defined in the claims.

Wherefore I claim:

1. An electric heater comprising an elongated housing structure providing an elongated outwardly directed cavity, an elongated resistor element disposed in said cavity and extending longitudinally thereof and provided at its ends with electrical connection terminals, each of said terminals comprising a tongue and a bolt connection for securing an electrical supply connector, mounting means secured within said cavity at longitudinally spaced-apart portions of said housing, each of said mounting means having a recess for slidably receiving and holding a tongue of a respective terminal, and said mounting means being spaced-apart a lesser distance than the distance between said terminals so that said element is assembled with said mounting means by inserting one tongue into a recess of one mounting means and longitudinally moving said element toward said one mounting means to dispose said one tongue inwardly of its recess sufficiently so that the opposite tongue may be aligned with the recess of the other mounting means, and longitudinally moving said element in an opposite direction and withdrawing said one tongue from its recess sufficiently to seat said other tongue in its recess whereby said element is properly supported between said mounting means, and each of said mounting means having a slot for receiving a portion of the bolt of the respective terminal, each of said slots providing an abutment wall engageable with a respective bolt portion to restrict longitudinal movement of said element an amount sufficient to prevent disassembly of said element from said mounting means, assembly and disassembly of said element being effected when said bolt portions are withdrawn from respective slots.

2. An electric radiant heater comprising an elongated housing open at one side to provide a heating element receiving cavity, a pair of mounting members disposed in longitudinally spaced relation within said cavity, said members each having an elongated guide recess and an elongated guide slot disposed in spaced substantially parallel relation, said guide recesses and slots being respectively open and closed at their inner ends in respect to the ends of said housing, an elongated heating element carried by said members within said cavity, and a pair of tongue members secured to the opposite ends of said heating element for connecting said heating element to a source of electric current, the free ends of said tongue members slidably engaging said mounting member recesses for removably securing said heating element to said mounting members and to compensate for longitudinal expansion and contraction of said element, and retractable stop means fitting within said slots when in locking position to prevent inadvertent removal of said heating element, and being withdrawable from said slots to provide for removal of said heating element.

3. An electric radiant heater comprising an elongated housing open at one side to provide a heating element receiving cavity, a pair of mounting members disposed in longitudinally spaced relation within said cavity, said members each

having an elongated guide recess and an elongated guide slot disposed in spaced substantially parallel relation, said guide recesses and slots being respectively open and closed at their inner ends in respect to the ends of said housing, an elongated heating element carried by said members within said cavity, and a pair of tongue members secured to the opposite ends of said heating element, each of said tongue members having a movable screw member thereon disposed within the guide slot of a said mounting member and for connecting said heating element to a source of electric current, the free ends of said tongue members slidably engaging said mounting member recesses for removably securing said heating element to said mounting members and to compensate for longitudinal expansion and contraction of said element, the free ends of said screw members being positioned for engagement with the closed ends of said slots when said screw members are in position to connect said heating element to said source of electric current to limit sliding movement of said tongue members along their recesses and to prevent unintentional removal of said heating element from mounted position, and said screw

members being movable to retract their free ends from engagement with the closed ends of said slots to provide for sliding movement of the said tongues an amount sufficient to clear a tongue from its recess.

JOSEPH McORLLY.
